UNITED STATES PATENT OFFICE.

MORRIS I. COHEN, OF CHICAGO, ILLINOIS.

DESIGN FOR A FIREPLACE-FRONT.

SPECIFICATION forming part of Design No. 26,367, dated December 1, 1896.

Application filed October 3, 1896. Serial No. 607,807. Term of patent 3¹ years.

To all whom it may concern:

Be it known that I, MORRIS I. COHEN, a citizen of the United States, residing at Chicago, in the county of Cook and State of Illinois, 5 have invented and produced a new and original Design for Fireplaces, of which the following is a specification, reference being had to the accompanying drawing, which is a view in front elevation of a fireplace, showing my 10 design.

The frame or front is of rectangular shape with flat sides F, having pillars in relief, comprising the rectangular base portions A and the similar top portions A⁵, the spirally-twisted portions A¹, the scalloped circular portions A², the longitudinally-fluted tapering portions A³, and the heads A⁴. The portions A A⁵ are provided centrally with transverse elongated C-shaped figures q, turned toward 15 each other and inclosing circumferentially-beaded oval figures t, with E-shaped figures 20 above and below, as shown.

B is the top panel of the frame, beaded about its edges and provided centrally with 25 a ring-backed rosette-like device p, representing petals radiating from a common center, at which is located a button r. Extending lengthwise of the top panel from its ornamented center are devices representing a species of lily l, having dentated calyxes l' and protruding stamens k, the anthers n of which 30

latter in turn bear leaves m of peculiar design.

E is the bottom piece of the frame, having irregularly-shaped figures c symmetrically 35 disposed with reference to the center.

C are doors of hammered metal, each having beaded edges and provided centrally with a shield device h, partially encircled with floral wreaths i i, and at the top and bottom are 40 open-work devices f f, representing sections of twisted rope extending across each door.

D is the hood, having a central vase design g, from which emanate traceries d, symmetrically arranged with reference to the center. 45

F' is the open trellis-work covering of the ash-pit, beaded about its edges and symmetrized with relation to the general design of the fireplace.

What I claim is—

1. The design for a fireplace-front, substantially as herein shown and described. 50

2. In the design for a fireplace-front the door substantially as herein shown and described.

3. In the design for a fireplace-front the hood substantially as herein shown and described. 55

MORRIS I. COHEN.

In presence of—

M. J. FROST,
J. H. LEE.
